CLAIM

The ornamental design for a display screen with icon, as shown and described.

DESCRIPTION

FIG. 1 is a front view of a display screen with icon showing our new design;

FIG. 2 is a front view of the display screen with icon of FIG. 1 with a region for enlargement indicated by broken-line indicia; and,

FIG. 3 is an enlarged view of FIG. 2.

The “FIG. 3” indicia shown in FIG. 2 forms no part of the claimed design. The broken line showing of the remainder of the display screen is for environmental purposes only and forms no part of the claimed design.
